E. THOMPSON.
ELECTRICAL WALL SWITCH.
APPLICATION FILED FEB. 13, 1920.

1,389,713.

Patented Sept. 6, 1921.

UNITED STATES PATENT OFFICE.

EMIL THOMPSON, OF OMAHA, NEBRASKA, ASSIGNOR OF ONE-HALF TO RANGVAL OLESON, OF OMAHA, NEBRASKA.

ELECTRICAL WALL-SWITCH.

1,389,713.

Specification of Letters Patent. Patented Sept. 6, 1921.

Application filed February 13, 1920. Serial No. 358,333.

To all whom it may concern:

Be it known that I, EMIL THOMPSON, a citizen of the United States, residing at Omaha, in the county of Douglas and State 5 of Nebraska, have invented certain new and useful Improvements in Electrical Wall-Switches; of which the following is a specification.

The present invention relates to electric 10 switches, and more particularly to a device for facilitating the installation of a switch in a wall.

An object of the present invention is to provide a holder or carrier for a switch of 15 common form, by means of which the common form or type of switch may be conveniently and easily mounted in a wall in lieu of the specially constructed and expensive switches and housing now in use.

20 Another object of the invention is to provide a switch holder or support adapted to take the place of the wall boxes now commonly employed, and to permit the use of the common rotary snap switch in walls, 25 and in such position that this type of switch may be entirely housed behind a cover plate substantially flush with the outer surface of the wall.

A further object of the invention is to 30 provide a holder or support which is of cheap construction and adapted to hold a relatively cheap switch in the same position, flush with the surface of a wall, as the more expensive and peculiarly constructed 35 switches are mounted; and to provide a holder of this character which is adapted to accommodate fastening devices at selective points for engagement with the laths of the wall irrespective of the ragged 40 even ends and the spacing apart of the laths near the margin of the recess in the wall.

A still further object of this invention is to provide a holder or support for an ordinary 45 switch which may be quickly and economically stamped up from sheet metal, and which is constructed to provide a protection for the heads of screws, or the like, employed in securing the holder to the wall; 50 and which affords a substantial support for a cover plate adapted to house the holder and the switch within the wall.

The above, and various other important 55 objects and advantages of this invention will in part be described in, and in part be

understood from, the following detailed description of the present preferred embodiment, the same being illustrated in the accompanying drawing, wherein:

Figure 1 is a sectional view partly in elevation through a holder constructed according to the present invention as applied to a wall and supporting a common type of snap switch.

Fig. 2 is an outer face view of the switch 65 holder with a switch therein.

Fig. 3 is a rear face view of the same.

Fig. 4 is a plan view of the base plate of the holder.

Fig. 5 is an edge view of the same, and 70 Fig. 6 is a longitudinal section taken through the base plate.

Referring to the drawing, and first to Fig. 1, 10 designates laths of a wall which are supported in the usual manner upon stud- 75 ing or the like, not shown, and which support a facing of plaster 11 applied in the ordinary manner.

The wall, designated generally by 11, is provided with a recess or opening to receive a switch, and the laths 10, about the margin of the opening, terminate in ends 12 which are usually ragged and uneven, and Fig. 1 shows the ends 12 of the laths terminating short of the marginal edge of the 80 opening in the wall 11. This is a condition usually met with in the forming of recesses or openings in walls as it is impractical to cut or break the laths 10 with any degree of accuracy with respect to the size of the 85 opening or recess.

13 designates the base of a common type of a rotary snap switch equipped with a housing 14 mounted on the base and provided with a knurled or otherwise roughened thumb piece 15 arranged exteriorly of the casing 14 to be grasped between the fingers for operating the switch. The base 13 of the switch is provided, as seen in Figs. 1 and 3, with lateral openings 16 to receive 100 wires, and binding screws 17 mounted in the back of the base for securing the wires in the openings 16. This is the usual construction of snap switch which may be bought on the market at a relatively cheap 105 figure. The present invention provides a holder for supporting this relatively economical and common type of snap switch in the opening in the wall, and to take the place of the usual junction or wall box with 110

its appurtenances and specially constructed switch.

The holder of this invention comprises a base plate which may be made integral from sheet metal and which, as shown in Figs. 4, 5 and 6, may be stamped to provide an intermediate strap or arched portion 18 adapted to fit more or less snugly in the opening of the wall 11 and to have its end portions or wings 19 lie against the outer surface of the wall 11. The wings 19 are preferably of greater width than the strap or arched portion 18 of this base plate, the wings being equipped with a plurality of spaced apart openings 20 adapted to selectively receive therein fastening screws 21, or the like, by means of which the base plate, generally indicated at 18, may be mounted in the recess of the wall. In the upper part of Fig. 1 the full lines disclose the fastening screw 21 arranged in an opening 20 of the wing near the inner edge of the latter. Should however the laths 10 be too short to catch the screw thus shown, the screw 21 may be positioned in an outer opening 20 of the wing in order to catch the laths 10 at a point more remote from the recess in the wall as shown in dotted lines. The wings 19 are of greater width than the strap 18 for the purpose of accommodating the fastening screws 21 to the intermediate portions of laths, so that the screws need not be driven into the wall between the spaced edges of the laths. In other words, the holder 18 is so constructed as to accommodate fastening screws 21 in practically any selected position to secure a firm hold upon the laths 10 and thus support the base plate 18 rigidly upon the wall by employing but one screw 21 at each end of the base plate. Of course any number of screws may be used, but it is found that one screw in each end of the base plate, when properly located, is sufficient to rigidly hold the base plate in the wall.

The strap of the base plate has a flat counter sunk bottom against which the base 13 of the ordinary switch is adapted to be seated, and screws 22 are passed through suitable openings formed in the bottom of the strap 18 to register with the usual openings found in the base 13 of the switch to secure the latter rigidly upon the base plate.

The base plate of the present invention is therefore adapted not only to be secured to walls with laths differently located and of different lengths, but also is adapted to the ordinary switch to support it without alteration in construction or any additions thereto.

For the purpose of housing the heads of the screws, without forming counter sinks in the wings 19 of the base plate, the opposite edges of the wings 19 are struck up or outwardly to form relatively shallow flanges 23 serving also as supports for a cover or

face plate 24 secured over the opening or recess in the wall. The cover plate 24 is provided with a central opening 25 adapted to fit over and about the outer end of the casing 14 of the switch to house the latter in the wall and center the face plate 24 about the switch. The face plate 24 is provided with an inwardly extending marginal flange 26 substantially closing the spaces between the flanges 23 of the wings and serving, as shown in Fig. 3, to hold the face plate and the switch from sagging upon the base plate.

From the above, it is thought that the installation and use of the holder will be apparent, for when the opening is formed with the wall 11, the strap 18 of the base plate is inserted in the opening and the screws 21 are secured through selected openings 20 of the wings to secure the desired purchase upon the laths 10 for supporting the base plate. The snap switch is first secured to the bottom of the base plate 18 by the screws 22 in the same manner as is usual in securing the snap switch to any support. The cover plate 24 is now fitted over the front of the switch and against the flanges 23 of the base plate, screws 27 being secured through the upper and lower portions of the base plate and threaded in suitable openings 28 into the base plate.

The holder thus supports the ordinary snap switch in a recess in the wall and houses or covers the switch in such a manner that the knurled thumb piece 15 only projects from the wall and is in such position that it may be readily grasped for operating the switch. The holder thus comprises but two parts, a base plate and a cover plate, and these parts may each be formed from a single blank of sheet metal or the like so that the device may be economically manufactured and is strong, rigid, and durable in construction.

It is of course understood that various changes and modifications may be made in the size, form and proportions of the above disclosed embodiment of this invention without departing from the spirit thereof, such changes and modifications being restricted only by the scope of the following claim.

What is claimed is:—

In combination, a base plate of narrow construction adapted to extend diametrically across the base of a switch casing, narrow straps extending from said base plate and being bent at substantially right angles so as to lie along the upper and rear portions of the switch casing, said straps being made in one piece with the base plate and having their outer ends turned in opposite directions at right angles to the planes of the straps, wings made in one piece with the out-turned portions of said straps, said wings being extended to opposite sides of the straps and being provided with perforations therein, fas-

tening means passing through the perforations and securing the wings to a support, said wings being provided at their lateral edges with forwardly over-turned flanges 5 extending outwardly at substantially right angles to the planes of the body portions of the wings, the flanges of the upper and lower wings extending substantially in vertical alinement, and a cover plate fitted over and concealing the wings and straps and having 10 its interior face adapted to come into contact only with said flanges, fastening means passing through said cover plate and engaged with the outwardly turned portions of 15 said straps, said cover plate provided with marginal flanges bent rearwardly at an obtuse angle to the plane of the cover plate, the upper and lower flanges of the cover plate adapted respectively to engage the upper and lower ends of the flanges on said wings 20 whereby to center the cover plate in a vertical direction and to guide the cover plate into place by the engagement of the obtuse flanges thereon with the upper and lower edges of the flanges on the wings, substantially as described.

In testimony whereof, I have affixed my signature in presence of two witnesses.

EMIL THOMPSON.
